UNITED STATES PATENT OFFICE

MILTON WILLIAMS SMITH, OF CALDWELL, NEW JERSEY

GRASPING DEVICE

Application filed March 12, 1929. Serial No. 346,427.

The invention relates to a grasping device for recovering or removing articles from inaccessible places and is particularly adapted for receiving broken rear axles from automobiles.

The axles usually break near the differential as the axle is weakest there as it is cut for the reception of a spline. The short stub remaining is removed at present by taking off the wheel and removing the axle from the other side of the car and then by means of a bar the part of the broken axle is driven out.

The object of this invention is to provide a tool that saves the time necessary for this removal of parts from the other side of the car and that can be used to grasp the stub and pull it out.

The object of the invention is also to provide a tool that is simple and cheap and that has certain details of construction that make its insertion and operation both rapid and easy.

The invention is illustrated in the accompanying drawing in which Figure 1 is a top view of a device embodying my invention. Figure 2 is an enlarged section of the end of the handle showing the jaws closed and also showing, in dotted outline, the jaws when open. Figure 3 is an end view of Figure 2 with the jaws shown in open position.

The handle part comprises a tube 10 of material length in order to allow it to pass onto the axle housing of an automobile as far as the differential. The tube 10 has a transverse handle 11 to provide for easier handling. A rod 12 is slidable in the tube and a spring 13 is interposed between the end of the tube 10 and a finger piece 14 on the rod 12 to yieldingly hold the rod in retracted position to force the jaws of the device toward a closed position.

The jaws 15 are hinged to the end of the tube 10. The jaws have their ends formed into knuckles 16 which flank the knuckles 17 on the tube. A pin 18 passes through the knuckles to form a pintle in each hinge. The knuckles 17 are made by slitting the tube and rolling back the material to form these knuckles thereby providing openings or slits

19 which are disposed to allow the jaw-operating links to swing outwardly when the jaws are separated.

The jaws are connected to the end of the rod 12 by the two links 20 which are pivoted to the lugs 21 on the jaws and to the end of the rod.

The jaws are broadened at the ends and have the curved outer edges 22, to grasp the outer surface of an axle that is to be withdrawn.

The jaws are shallow at their ends 23 to allow the jaws to act as a tapered end on the device, as will be seen from Figure 2 and the article can be inserted with ease. When it engages or nearly engages the axle the finger piece 14 is pushed in and this forces the rod 11 to cause the links 20 to spread the jaws. The slits 19 allow the links 20 to move outwardly and the jaws can be swung to a wide open position to allow them to encompass the stub of an axle and then close on it to give the jaws a good purchase. This is due to the links engaging the jaws intermediate the ends of the jaws and a slight movement of the rod 12 causes a relatively wide movement of jaws as will be seen from the dotted position of these parts shown in Figure 2.

Slight changes can be made in the form of the device without departing from the scope of the invention as defined in the claim.

I claim:—

A grasping device comprising a tube and slotted at the end and on opposite sides, the material slotted being rolled back on the outside of the tube to form knuckles, jaws having knuckles hinged to the knuckles on the tube, a rod slidable in the tube, links pivoted to the rod and the jaws and disposed so as to pass out through the slits when the rod is pushed to open the jaws.

In testimony whereof I affix my signature.

MILTON WILLIAMS SMITH.
